UNITED STATES PATENT OFFICE.

ALEXANDRE BERTIER, OF HANNIBAL, MISSOURI.

IMPROVEMENT IN STATION AND STREET INDICATOR FOR RAILROAD-CARS.

Specification forming part of Letters Patent No. **38,143**, dated April 14, 1863.

To all whom it may concern:

Be it known that I, ALEXANDRE BERTIER, of Hannibal, in the county of Marion and State of Missouri, have invented a new and Improved Station and Street Indicator for Railroad-Cars; and I do hereby declare that the following is a full, clear, and exact description of the same, reference being had to the accompanying drawings, making a part of this specification, in which—

Figure 1 is a side view of a railroad-car, partly in section, with my invention applied to it; Fig. 2, a transverse vertical section of the same, taken in the line $x x$, Fig. 1. Fig. 3 is also a transverse vertical section of the same, taken in the same line, $x x$, as Fig. 2, but looking in the opposite direction; Fig. 4, a detached view of a part pertaining to the invention.

Similar letters of reference indicate corresponding parts in the several figures.

This invention consists in the employment or use of an endless band, having the names of the stations or streets marked upon it, and placed within a suitable case within the car, in combination with a bell, a combined bell-hammer and stop, and a band-moving mechanism, all arranged as hereinafter described, whereby the several stations or streets will, as they are reached, each be indicated or shown to the passengers in the car, and an alarm sounded, so as direct the attention of the passengers to the indicator.

To enable those skilled in the art to fully understand and construct my invention, I will proceed to describe it.

A represents a railroad-car, which may be of the usual or any proper construction, and B B represent the rails on which the car runs.

C is a case, which is placed in the car at one end of it, and has two rollers, D D', fitted in it, one being at the upper and the other at the lower part of the case, one roller being directly over the other, and both in the same axial plane.

E is an endless band, which is fitted on the rollers D D', and may be constructed of any suitable cloth or flexible fabric. This band has the names of the several stations on the route painted or marked upon it, at equal distances apart, in any suitable way, and successively as they occur on the line of the road. (See Fig. 2.) The upper roller, D, has its shaft

a extending through one side of the car, and on the outer end of said shaft there is placed a star or pointed wheel, E, which is shown clearly in Fig. 1.

Within the case C, or adjoining it at one side, and near one end of the upper roller, D, there is secured a bell, F, and just below said bell there is a spring-hammer, G, which may be constructed of an elastic rod bent over backward at its inner or disengaging end, as shown at b, and then curved upward, as shown at c. (See Fig. 4.)

In the end of the roller D, which is near the bell and spring-hammer G, there are fitted pins or rods d, at equal distances apart, near the periphery of the roller. These pins or rods, when the roller D is rotated, will strike the end b of the spring-hammer.

The end of the shaft a of the roller D which is opposite to the end where the star or pointed wheel E' is secured passes through the side of the case C, and has a pulley, H, upon it, to which a cord, e, is attached, said cord having a weight, I, at its end. (See Fig. 2.)

J is an upright post, which is placed at one side of the railroad, and has an arm, K, secured to its upper end by a pivot, f. The outer end of this arm is connected to a spring, L, the lower end of which is attached to the post J. On the inner end the arm K—that is to say, the end which extends toward the railroad—has a thimble or tube, M, fitted loosely upon it. This thimble has such a relative position with the star or point wheel E' that the arms of the latter will come in contact with the former as the car A passes the post J, and by this means the roller D and band E are moved, the names being at such a distance apart on the band E as to cause one to be brought in line with or directly opposite a slot in the front of the case C. Each time the band E is thus moved a pin or rod, d, of the roller D will strike the end b of the hammer G and force it down, and when the pin or rod has passed the end b the hammer will, by its own elasticity, spring upward, and the curved part c strike the bell F, thereby sounding an alarm to direct the attention of the passengers to the indicator, where the name of the station is exposed. The weight I serves to keep the pins or rods d in contact with the end b of the hammer G, the latter serving as a stop

to prevent the casual movement of the band E, the hammer being sufficiently stiff to resist the gravity of the weight I. The number of pins or rods *d* at the end of the roller D is equal to the number of points or arms of the wheel E'; and I would remark that there is a post, J, placed at each side of the road or track *h*, so that the band may be operated when the car is traveling in either direction.

In Figs. 1 and 3, a modification of the previously-described device is shown for a city railroad-car indicator. L is the band placed on rollers M M', and having the names or numbers of the streets marked on it. The band is placed within a case, N, having a slot, *g*, in its front side to expose successively the names of the streets as the latter are reached. In this arrangement the star or pointed wheel O is attached to the lower roller, M, and is actuated by a small projection, P, which will not serve as an obstruction in the street.

I do not claim the endless band separately,

for that has been previously used for the purpose herein specified; but

I do claim as new and desire to secure by Letters Patent—

1. The endless band, with a star or pointed wheel attached to one of its rollers or the shaft thereof, and a projection at the side of the track or road to actuate said wheel, in combination with a bell, combined spring-hammer and stop, and the pins or rods *b*, the latter being attached to the roller aforesaid, and all arranged to operate substantially as and for the purpose herein set forth.

2. The weight I, applied to one of the rollers of the endless band, when used in combination with the other parts of the band-moving mechanism, for the purpose specified.

ALEXANDRE BERTIER.
